ELEVATOR UNIT FOR USE WITH A BATHTUB

Lucy L. Meyer, Oakland, Calif.

Application March 3, 1954, Serial No. 29,302

Term of patent 14 years

(Cl. D4—3)

To all whom it may concern:

Be it known that I, Lucy L. Meyer, a citizen of the United States, residing at Oakland, county of Alameda, State of California, have invented a new, original, and ornamental Design for an Elevator Unit for Use With a Bathtub, of which the following is a specification, reference being had to the accompanying drawings, forming a part hereof, wherein,

Figure 1 is a perspective view of an elevator unit for use with a bathtub embodying my new design and with the platform being in a raised position.

Figure 2 is a similar view with the platform in a lowered position; and

Figure 3 is an end view of Figure 2.

The rear of the casing is plain. The bathtub shown in broken lines is disclosed for illustrative purposes only.

I claim:

The ornamental design for an elevator unit for use with a bathtub, substantially as shown and described.
